UNITED STATES PATENT OFFICE.

JOHN W. MURRAY, OF BUFFALO, NEW YORK.

DESIGN FOR A GLASS DISH.

49,712.

Specification for Design. Patented Sept. 26, 1916.

Application filed March 24, 1916. Serial No. 86,514. Term of patent 3½ years.

To all whom it may concern:

Be it known that I, JOHN W. MURRAY, a citizen of the United States of America, and a resident of the city of Buffalo, county of Erie, and State of New York, have invented a new, original, and ornamental Design for Glass Dishes, of which the following is a specification, reference being had to the accompanying drawings, forming a part thereof.

The figure in the drawings is a plan view of a glass dish, showing my design.

I claim:

The ornamental design for a glass dish as shown.

In testimony whereof, I have hereunto signed my name in the presence of two subscribing witnesses.

JOHN W. MURRAY.

Witnesses:

J. WM. ELLIS,
